UNITED STATES PATENT OFFICE.

CHARLES SCHOLTZ, OF SHARON, PENNSYLVANIA, ASSIGNOR TO SHARON STEEL HOOP CO., OF SHARON, PENNSYLVANIA, A CORPORATION OF PENNSYLVANIA.

PICKLING AND CLEANING APPARATUS.

1,368,357.

Specification of Letters Patent. Patented Feb. 15, 1921.

Application filed September 15, 1920. Serial No. 410,401.

To all whom it may concern:

Be it known that I, CHARLES SCHOLTZ, a citizen of the United States, and a resident of Sharon, in the county of Mercer and 5 State of Pennsylvania, have invented certain new and useful Improvements in Pickling and Cleaning Apparatus, of which the following is a specification.

My present invention relates to improvements in continuous pickling and cleaning apparatus and aims to provide a simple, economical and efficient form of apparatus in which the sheet metal plates will be carried through the tank or tanks in a manner 15 which will afford a maximum contact with the treating liquid.

The invention further aims to provide a construction by which the plates may be readily fed to and discharged from the conveyor means.

With these and other objects in view the invention includes the novel features of construction and arrangement and combination of parts hereinafter described and particularly defined by the appended claims.

An embodiment of my invention is illustrated in the accompanying drawings in which:

Figure 1 is a plan view of a pickling apparatus constructed in accordance with my invention.

Fig. 2 is a sectional elevation.

Fig. 3 is a transverse section on line 3—3 of Fig. 1.

Fig. 4 is an enlarged plan view of a section of one of the endless conveyors, and

Fig. 5 is a side elevation of the same.

Figs. 6 and 7 are enlarged sectional details.

Referring by reference characters to these drawings, A, B, and C designate a series of tanks which is intended to be representative of any desired number. In the embodiment shown in the drawings A is a pickle or 45 cleaning tank which is made preferably somewhat longer than the succeeding tanks as shown, B a rinse tank, and C a tank containing a material to keep the metal from corroding, as will be well understood by those skilled in the art. Endless conveyor means are provided for conveying the sheets or plates to be pickled through the tanks, it being understood that any desired number of conveyors may be used according to the

nature of the plates to be treated. In the drawings I have shown two conveyors designated by the letter D. Each of these conveyors preferably comprises two sets of links b and b', the links b being plain chain links and the links b' being provided with rigid 60 parallel fingers K' spaced sufficiently far apart to provide intervening seats or recesses for receiving and holding the plates which are indicated at K. The links are connected by pivot pin b² upon which are journaled 65 antifriction rollers b³ which are designed to engage with the guides as hereinafter described.

At the opposite ends of the series of tanks and at points intermediate of the tanks are 70 located a series of supporting and guiding means in the shape of sprocket wheels G, G', G² and G³ over which the conveyors pass and by which it is moved, and the conveyors or chains are so arranged or disposed with relation to the sprocket wheels that slack portions are formed which depend into the tanks as clearly shown in Fig. 2.

Within the tank are provided guides or tracks F, F', and F² upon which the rollers 80 of the chain or conveyor links travel, these guides or tracks being continuous from one end of each tank to the other, and inclining or curving downwardly from each end to or near the bottom of the tank.

Beneath the tanks are longitudinal guide rails or tracks L which are designed to support and guide the portion of the conveyor passing underneath the tanks on its return to the feed end.

The sprocket wheels G, G', G² and G³ are all designed to be driven in unison by any suitable means so as to always preserve the slack, and this may be conveniently accomplished by providing the shafts g upon 95 which the sprocket wheels are mounted with bevel gears g' meshing with corresponding bevel gears e on a longitudinal shaft E designed to be driven by any suitable reducing power transmitting means I, such as conventionally illustrated in the drawings, from the electric motor M.

At one end, the feed end, of the series of tanks is located a feed table H designed to receive a pile of the plates to be pickled, and 105 this table has a downwardly inclined portion provided with fingers or projecting bars h which are designed or positioned to over-

lap the fingers of the conveyers. To properly position the links as they pass up by the edge of the table so that the plates supported by the table will be in perfect alinement 5 with the slots or recesses between the fingers of the conveyers, I provide additional supporting and guiding sprockets G⁴ which may be idle sprockets as shown, and the plates may be slid into the spaces between the 10 fingers of the conveyers by hand or in any suitable manner.

At the delivery end of the apparatus I provide a collecting device in the shape of a chute J having collecting fingers or projections which overlap the fingers of the conveyers and serve to strip or remove the 15 plates automatically from the fingers K' as the sprocket chains or conveyers pass around the final sprocket wheels G³. The chute is 20 preferably provided with a horizontal portion J' which is provided with plate retaining projections J'', this arrangement being intended to be representative of any suitable collecting device.

25 I prefer to arrange the fingers of the conveyer links so that they incline backwardly with relation thereto as shown.

Having thus described my invention what I claim is—

30 1. In a continuous pickling apparatus a tank, an endless conveyer having a portion depending into the tank, said conveyer having a plurality of closely spaced rigid members having parallel walls forming 35 pockets for holding plates on edge and means for moving said conveyer.

2. In a continuous pickling apparatus a tank having a stationary guiding means extending from one edge of the tank to the 40 opposite edge and depending into the tank between said edges, endless conveyer means having a slack portion coöperating with said guiding means, and plate engaging devices carried by said endless conveyer, said 45 plate engaging devices being inclined to the plane of the conveyer.

3. In a continuous pickling apparatus, an endless conveyer comprising two sets of links pivotally connected together, one set 50 of links being plain chain links, and the

other set being provided with spaced rigid projections.

4. In a continuous pickling apparatus, an endless conveyer comprising two sets of links pivotally connected together, one set 55 of links being plain chain links, and the other set being provided with spaced rigid projections, said projections being inclined to the plane of the links.

5. In a continuous pickling apparatus, a 60 tank, a guideway therein, and an endless conveyer comprising pivotally connected link members having rigid plate holding 65 projections, and rollers connected with the link pivots and adapted to coöperate with said guideway.

6. In a continuous pickling apparatus a tank, endless conveyer means arranged to pass through the tank, said conveyer means carrying spaced rigid fingers, supporting 70 and guiding means at the receiving end of the tank over which said conveyer means passes, and a feed table at one end having inclined spaced fingers overlapping said 75 conveyer means.

7. In a continuous pickling apparatus, a tank, an endless conveyer means arranged to pass through the tank, supporting means for said conveyer at the delivery end of the tank, spaced plate engaging fingers carried 80 by said conveyer means, and inclined stationary fingers arranged to coöperate with said conveyer at the delivery end to automatically remove the plates from said plate 85 engaging fingers.

8. In a continuous pickling apparatus, a plurality of tanks, sprocket wheels located between the tanks and at the ends of the series, endless chain conveyer means passing around said sprocket wheels beneath the 90 tanks, and having slack portions depending into the tanks, and means for driving all of said sprocket wheels in unison, closely spaced parallel fingers or projections carried by said conveyer means, and means for feeding plates edgewise between said fingers or projections at the initial end of the apparatus.

In testimony whereof I affix my signature.
CHARLES SCHOLTZ.
